CLOCK

Harold D. Fetty, Birmingham, Mich., assignor to General Time Corporation, New York, N.Y., a corporation of Delaware

Filed May 2, 1960, Ser. No. 60,514

Term of patent 14 years

(Cl. D42—7)

FIG.1

FIG.2

FIG.3

FIG. 1 is a front elevational view of a clock embodying my new design;

FIG. 2 is a top plan view; and

FIG. 3 is a side elevational view of said clock.

I claim:

The ornamental design for a clock, as shown.
